COMBINED SHOE GUIDE AND BULL PLUG
FOR WELL CASINGS

Reuben C. Baker, Coalinga, Calif.

Application January 31, 1928, Serial No. 250,831

2 Claims. (Cl. 166—9)

This invention relates to deep well drilling equipment and particularly pertains to a device for use in guiding and floating a well casing into place in a bore.

5 Prior to my invention guide shoes and floating plugs have been provided which were adapted to be fitted to the lower end of a well casing in the casing shoe for guiding and floating the casing into place in the hole.

10 In some instances the guide shoe and floating plug were combined into one element commonly known as a bull plug which had a semi-spherical lower end projecting from the end of the shoe and entirely closing the same. As this end was semi-spherical it would guide the casing in the hole and as it entirely closed the end of the casing, the casing could be floated into place; that is, the resistance offered by the fluid in the well to displacement by the casing would to a 15 certain extent support the casing and relieve the derrick somewhat of its weight.

In other instances the guide shoe was merely an open ended sleeve having a rounded or tapered lower end adapted to guide the casing in the hole. When using such a shoe the fluid was free to pass upwardly into the casing as the casing was lowered.

All of these prior devices were formed of metal in most instances friable material, such as cast iron, because it was necessary to drill or break them out after the casing was into place so that the drilling could be proceeded with. These devices have not proven entirely satisfactory for the reason that after they were broken or drilled out, large pieces of metal remained in the hole which had a very injurious effect on the drilling tools utilized when continuing the drilling.

The present invention has for its principal object the provision of a guiding and floating device which may be utilized as a casing guide or as a combined guide and float plug which is formed entirely of non-metallic material such as cement.

45 In carrying out the invention into practice, I form a plug in the end of a casing shoe, which plug is constructed entirely of cementitious material and is formed with a guide portion at its lower end projecting beyond the end of the shoe. This guide portion is substantially semi-spherical and of a diameter the same as the exterior diameter of the shoe, so that it will act to guide the end of the casing when it is lowered in the hole. A passageway of comparatively 50 small diameter is formed centrally and longi-

tudinally through the shoe, so that the shoe may be utilized as a plain guide. This passageway extends straight through the center of the plug and due to the fact that the plug is of considerable length this passageway will create a nozzle effect to enable a forceful stream of water to be ejected from the lower end of the plug for the purpose of supporting a washing down action when desired. When desiring to use the device as a bull plug, the lower end of this passageway 10 is plugged by cementing or otherwise securing a tapered plug of cementitious material in the lower end thereof. The insertion of this plug entirely closes the lower end of the casing and enables the latter to be floated into place in the 15 hole.

One form which the invention may assume is exemplified in the following description and illustrated by way of example in the accompanying drawing, in which:

20 Fig. 1 is a view in central vertical section through a device embodying the preferred form of my invention, showing the device as it is when used as a plain guide.

Fig. 2 is a similar view of the device when 25 used as a guiding and floating plug.

Fig. 3 is a view of the plug utilized to convert the guide into a guiding and floating plug.

Referring more particularly to the accompanying drawing, 10 indicates a hollow cylindrical 30 member preferably formed of steel. This member is commonly termed a casing shoe and is interiorly threaded as at 11 so that it may be connected to the lower end of a string of well casing. Between the threaded portion 11 and the 35 lower end of the shoe its interior surface is formed with a plurality of annular locking grooves 12. Cast within this lower end of the shoe 10 is a plug 14. This plug is formed entirely of cementitious material. At its lower end this plug 40 is formed with a guide portion 15 which projects beyond the end of the shoe and which is of a diameter substantially the same as the exterior diameter of the shoe. This guide portion 15 is shown as substantially semi-spherical but it may 45 be tapered or torpedo-shaped if desired, as any of these shapes will act as guides to guide the lower end of the casing into place in the hole.

The plug 14 is formed with a longitudinally extending passageway 16 which extends centrally 50 through the device. In Fig. 1 this passageway is shown as unobstructed so that the device may be used as a plain shoe guide for a well casing, the guide portion of the plug guiding the casing into place and protecting the lower edges of the 55

casing shoe. The fluid in the hole may pass freely through the passageway 16. After the casing has been lowered into place, the plug may be broken or drilled out expeditiously.

5 In Fig. 2 I have shown the device as shown in Fig. 1 converted into a bull plug, which is in reality a guiding and floating plug. So that this conversion may take place, the lower end of the passageway 16 is tapered or flared as indicated 10 by the numeral 17. This tapered portion has its larger diameter at the extreme lower end of the plug. Intermediate its ends the tapered portion of the passageway is grooved as at 18.

To plug the passageway, I provide an insert 15 plug 19 which is tapered to correspond with the tapered portion of the lower end of the passageway. This plug is formed with a groove 20 adapted to register with the groove 18 in the passageway when the plug is inserted into place. 20 To secure this insert plug in place, grouting or cement is inserted between it and the sides of the passageway as indicated by the numeral 21 in Fig. 2. After the insert plug 19 has been secured in the lower end of the passageway, the 25 device 14 will entirely enclose the lower end of the casing so that it will act as a guiding and floating plug, which is commonly termed bull plug.

From the point of production this plug is a 30 very desirable article as all of the plugs may be cast the same. When a plain guide is ordered the plug is sold without modification and when a bull plug is ordered, the insert plug is cemented into place converting a plain guide into a bull 35 plug. If desired the device may be sold with the insert plug separate so that the user may convert the plug at his option.

The most important feature of the present invention is the fact that I have provided a plain 40 guide formed entirely of cementitious material,

and also a bull plug formed entirely of cementitious material. This is a very advantageous feature because it may be expeditiously removed from the lower end of the casing after it has served its purpose without leaving metallic pieces 5 in the hole, which are very injurious to drilling tools.

While I have shown the preferred form of my invention, it is to be understood that various changes may be made in its construction by those 10 skilled in the art without departing from the spirit of the invention as defined in the appended claims.

Having thus described my invention, what I claim and desire to secure by Letters Patent is: 15

1. In combination with a well casing, of a plug 20 of cementitious material formed in the end thereof, said plug having an uninterrupted passageway formed longitudinally therethrough, the lower end of the passageway having a tapered 25 portion, the larger diameter of the tapered portion being lowermost, and an insert plug fitting said tapered portion and adapted to be cemented therein to close said passageway, said insert plug being held in place solely by the cement. 25

2. In combination with a well casing, a casing shoe, a plug of cementitious material cast in the end of the casing shoe, said plug having a guiding portion extending beyond the lower end of the casing and of a diameter the same as the exterior diameter of the casing whereby to guide the casing when the same is lowered in a bore, said plug having an uninterrupted passageway formed longitudinally therethrough, and an insert plug adapted to be inserted in said passageway and cemented therein to close said passageway, said insert plug being held in place solely by the cement. 35
